UNITED STATES PATENT OFFICE

BENJAMIN F. FITCH, OF GREENWICH, CONNECTICUT, ASSIGNOR TO MOTOR TERMINALS COMPANY, OF WILMINGTON, DELAWARE, A CORPORATION OF DELAWARE

APPARATUS FOR TRANSFERRING FREIGHT

Original application filed October 23, 1929, Serial No. 401,816. Divided and this application filed October 29, 1930. Serial No. 491,929.

This invention relates to an apparatus for transferring freight from station platforms and the like, by the employment of automobile trucks having demountable bodies which 5 may be rolled from platform to truck and vice versa, and is a division of my application for Letters Patent, Serial No. 401,816, filed October 23, 1929. The general object of this invention is to provide simple and effective means for facilitating such rolling operation. More specifically, I provide the station platform with a trackway to receive the body and which may be elevated at its distant end to enable gravity to assist in rolling 10 a body from the platform onto a truck. Finally I provide means by which the tractive effort of the truck may be employed to tip the trackway on the platform when the body is to be rolled onto the truck.

15 The above outlined features will be hereinafter more fully explained in connection with the drawings which illustrate an embodiment thereof, and the essential novel characteristics will be summarized in the claims.

In the drawings, Fig. 1 is a side elevation of a truck and station platform equipped with my tipping trackway and showing the body in position on the platform before it has rolled onto the truck platform; Fig. 2 is a similar view showing the body in the act of rolling from the station platform onto the truck platform; Fig. 3 is a sectional elevation on a larger scale of the truck body and its trackway and the associated parts on the station platform; Fig. 4 is a similar view illustrating the station trackway elevated; Fig. 5 is a vertical section through the station platform lengthwise of the tipping trackway thereon; Fig. 6 is a cross section of the same in a vertical plane indicated by the line 6—6 on Fig. 5; Fig. 7 is a perspective of a stationary guide carried by the platform for causing the tipping of the platform trackway when drawn longitudinally outward; Fig. 8 is a vertical section through a rear portion of the truck and its trackway, being an enlarged section on the plane 8—8 on Fig. 3; Fig. 9 is a side elevation of the coacting leveling and locking parts caused by the plat-

form and truck, these parts being shown on a smaller scale in Fig. 3. Fig. 10 is a section in a horizontal plane indicated by the line 10—10 on Fig. 9.

As shown in Figs. 1 and 2, 10 designates 55 the fixed body of an automobile truck and 11 and 12 the wheels thereof, some of which are adapted to be driven by the power of the truck. The body may have a pair of longitudinal sills braced by suitable cross sills. 60 Surrounding this body is a frame 20 which has the usual longitudinal sills and cross members and carries as its top surface a pair of parallel trackways 26.

Figs. 1 and 2 show at A a demountable 65 automobile body which is a container with walls, floor, roof and suitable bracing and is provided with suitable doors indicated at a. This body has four or more wheels 70 (Fig. 6) in its floor frame which rest on the trackways 26 of the truck when the body is mounted thereon. The wheels may be flanged or the trackways flanged as desired. I prefer to make the wheels plain cylindrical members and flange the trackway, the 75 trackway being thus an upwardly facing shallow channel bar.

When the container or body is on the truck, it is positioned at its forward end by abutting a stop plate 27 on the frame and is held at its rear end by suitable gate or other cross member. I have shown such rear locking gate as an arm 28 rotatably mounted on a cross rod 21. Suitable means are provided for locking this bar in its upright position, as for instance, the latch 29 slidably mounted in the tipping frame and adapted to coact with the surface of the arm 28 and prevent rotation of the arm. The latch 29 may be operated by means of a bar 29a threaded to the latch and extending through the tipping frame where it may be bent downwardly so as to be grasped by the operator and readily be thrust inwardly to lock the arm or pulled outwardly to permit the arm to swing downwardly on its pivot, thereby releasing the body. The downwardly extending portion of the bar 29a may readily be locked to a suitable projection 29b on the frame by means of a suitable padlock or the like.

Suitable means are provided to bring the truck frame to a proper height as the truck backs into place. To effect this, I utilize the invention shown in my copending application No. 321,834, filed November 26th, 1929, and comprising rollers 50 and 51 mounted on shafts 52 and 53 journaled in brackets 54 rigidly carried by the truck frame 10 and depending therefrom. These 10 rollers are spaced apart a distance corresponding to the thickness of a horizontal ledge 40 projecting from the vertical wall of the station platform. This ledge is so arranged that when a truck carrying a maximum load backs into place the truck will stand at such elevation that the ledge 40 will engage the upper roller 50 which will thereby ride on top of the web suitably raising the truck body as it backs into place. If the 15 truck carries a minimum load (where there is no container on the truck) the ledge 40 will engage the lower roller 51 and will thus lower the truck body. Fig. 8 shows two aligned pairs of rollers 50, 51, which I find 20 a convenient arrangement.

It will be noticed that when a truck without a container backs into position and the ledge 40 engaging the rollers 51 draws down the frame, this action causes a compression 30 of the truck springs, thereby exerting a downward pressure on the wheels and increasing the traction power of the truck. This condition will exist as long as the truck is engaged by the ledge and proves 35 advantageous in starting the truck.

I have shown the platform abutment referred to as comprising a cross member 40 rigidly projecting from the vertical wall 41 of the station platform 42. This bumper 40 member may be in the nature of a horizontal web suitably braced by vertical webs indicated at 44 and having a head 45 whereby it may be effectively embedded in the material of the platform which may, for instance, be 45 of cement.

I provide the station platform with a 50 tippable frame having trackways adapted to register with the truck trackways and receive the wheels of the demountable bodies. Such station frame may be built up of longitudinal side rails 60, intermediate longitudinal rails 61 carrying trackways 62 and suitable cross members 63. The side members 60 carry several outwardly extending studs 65 55 on which are mounted rollers 66. These rollers extend into inclined openings in suitable blocks 71 secured to securing members 75 rigidly carried by the station platform 42.

I have shown the blocks 75 as having flanges 60 73 overlying the securing blocks 75 which are embedded in the cement of the platform, screws 76 rigidly connecting the parts together.

When the tipping frame on the station 65 platform stands with its outer end substan-

tially flush with the vertical wall 41 of the platform, as shown in Figs. 2 and 3, the tipping frame 60 is horizontal. This is the position which it occupies when the demountable body is being rolled from the truck onto the station platform. In this position, each of the rollers 66 occupy the lower or rearmost portion of the inclined stationary grooves 70, which portions are all on the same level. To enable the power of the truck to tip the inner end of the station frame upwardly, I make the inclined guides 70 successively steeper as one proceeds away from the edge of the platform and I provide means whereby the truck frame may be attached to the station frame 80 and move it longitudinally for a short distance as the truck moves away from the platform wall 42. This outward movement causes the rollers to ride up the successively steeper inclines 70 and thus tip upwardly the inner end of the frame, as indicated in Fig. 5.

To lock the truck to the station frame, I may avail myself of the locking bar 28 heretofore referred to. With that in view, I provide this locking bar with a downwardly or outwardly projecting latch portion 80 which may engage in an opening 81 in a suitable block 82 in the station frame adjacent its forward end. Thus, by turning down this locking bar, I at once leave the bridgeway 95 clear to or from the truck trackway and I lock the truck to the station platform. A short outward movement of the truck then does not change the close abutment of the station frame to the truck frame, but draws the station frame outwardly and tips its inner end upwardly so that the body thereon may be readily rolled onto the truck frame.

It will be seen that when a body loaded or unloaded is on a truck, it may be carried 105 by the truck in the usual manner. As the truck backs into the station if the station frame is projecting beyond the edge of the platform wall 41, the truck abuts it and shoves it inwardly during the time the truck 110 is being leveled and then the body may be shoved from the truck manually or automatically, as described and claimed in my copending application, Serial No. 401,816. Thus, irrespective of the position of the station frame at the beginning of the movement, the station frame will be in its inner and horizontal position when the truck has completed its backing movement and the forward end of its trackways is elevated. Now, by turning down the locking bar 28, the truck becomes locked to the station frame and the demountable body may be readily and safely 115 rolled off of the truck onto the station platform. It thus comes onto the station frame 120 which is horizontal and may be left there for loading and unloading, or if desired, may be rolled off of the station frame onto a stationary portion of the platform by any suitable means.

To transfer a body from the station platform to the truck, this body is first placed on the tipping frame 60 when it is horizontal and hence is at its innermost position. Now 5 the truck backs into place and the end gate 28 is hooked to the station platform frame, then the truck moves outward for a short distance under its own power which is readily accomplished because of the traction 10 given the truck by reason of its engagement with the bumper, as heretofore described. This outward movement of the truck elevates the inner end of the station frame. Now, the 15 movement of the truck stops and the body may be readily rolled by manual power down the incline of the station frame and onto the trackway on the tipping frame of the truck which is now horizontal. At the conclusion 20 of such operation, a very slight backward movement of the truck will relieve the pressure on the locking gate 28 and it may be swung into its vertical position to release the tipping platform of the station and at the 25 locking bar 29 may be shoved into engagement with the latch 28, thereby locking it in a position to act as a tail gate for the loaded body on the truck. Thus, as heretofore stated, I utilize the power of the truck to tip 30 the inner end of the body when it is on the platform to enable it to be readily rolled onto the truck.

I claim:

1. The combination with a truck, of a tilt- 35 able and shiftable support, means for attaching the truck to the support, whereby the truck in driving out may pull the support with it a short distance, and means whereby such outward movement of the support causes the elevation of its inner end to assist in 40 rolling a body from the support onto the truck.

2. The combination of a station having a truck pit and an elevated platform adjacent thereto, a longitudinally movable support 45 mounted on the elevated portion of the platform, means for anchoring the truck to the support, whereby the truck in driving out of the pit may pull the support with it a short distance, and means whereby such outward movement of the support causes the elevation of its inner end to assist in 50 rolling a body from the support onto the truck.

3. The combination with a truck, a demountable body adapted to be carried thereby, a station having a bodily movable tiltable frame, means whereby the outward movement of the frame tips the frame, said frame being adapted to carry the demountable body, and means for attaching the truck to said 55 frame whereby outward movement of the truck may tip the station frame.

4. The combination of a truck adapted to carry a demountable body on wheels, a station having a shiftable frame, and roller and inclined guide connections between the frame

and a stationary part of the station, whereby the shifting movement of the frame will tip its inner end upwardly, said station frame having a trackway for receiving the demountable body.

70

5. The combination of a truck adapted to carry a demountable body, a station having a movable frame, means whereby the longitudinal movement of the frame elevates the inner end of the frame, said frame being 75 adapted to carry a similar automobile body, and means for connecting the truck to the station frame to enable the truck to move the frame longitudinally while maintaining a trackway for the body from the frame to the truck.

6. The combination of a truck adapted to carry a demountable body, a station having a movable frame, means whereby the longitudinal movement of the frame outwardly 85 elevates the inner end of the frame, said frame having a trackway for carrying a similar automobile body, and a latch member serving in one position to hold a body on the truck and in another position to lock the truck to the station frame.

7. The combination of a station having a platform adapted to tip, a truck having a trackway, a demountable body, cooperating means on the truck and station to bring the truck to a definite height and maintain it for a short movement of the truck relative to the station, mechanism for raising the distant end of the platform, there being an operating connection between said mechanism and the truck.

8. The combination of a station having a platform and a truck runway, a highway truck adapted to travel on the runway, a tiltable frame on the station platform, mechanism for raising the distant end of the tilting frame, means for connecting said mechanism to the truck, a pair of leveling rollers carried by the truck frame, and an abutment projecting from the stationary platform adapted to project between said rollers and maintain such engagement for a short movement of the truck.

9. The combination of a floor, a platform mounted thereon for movement longitudinally outward a short distance, means for raising and supporting the inner end of the platform when so moved, and means for anchoring a truck to the outer end of the platform whereby the outward movement of the truck 115 will raise the inner end of the platform.

10. The combination of a truck, a demountable body adapted to be carried thereby, a station having a tippable trackway adapted to carry the demountable body, mechanism for raising the distant end of the trackway and an interlocking connection between said mechanism and the truck whereby movement of the truck raises the distant end 125 of the trackway.

130

11. The combination of a truck, a demountable body adapted to be carried thereby, a station having a tippable trackway adapted to carry the demountable body, 5 mechanism for raising the distant end of the trackway, and an operating connection between said mechanism and the truck whereby movement of the truck raises the distant end of the trackway, there being means for maintaining a suitable track for said body from the station to the truck during said tipping movement of the trackway.

12. The combination of an automobile truck carrying a trackway, a station having 15 a trackway adapted to register with that of the truck, said station trackway being tilt-able to raise the end distant from the truck, and means operable by the movement of the truck relative to the station for raising the 20 distant end of such station trackway to enable the rolling of a body thereon onto the truck, there being means to enable a close connection of such trackways during the rolling move-
ment.

25 In testimony whereof, I hereunto affix my signature.

BENJAMIN F. FITCH.
